US0D1010643S

(12) **United States Design Patent** (10) **Patent No.:** **US D1,010,643 S**
Tu (45) **Date of Patent:** **** Jan. 9, 2024**

(54) **LAPTOP COMPUTER**

(71) Applicant: **Lenovo (Beijing) Limited**, Beijing (CN)

(72) Inventor: **Chuantao Tu**, Beijing (CN)

(73) Assignee: **Lenovo (Beijing) Limited**, Beijing (CN)

(**) Term: **15 Years**

(21) Appl. No.: **35/515,125**

(22) Filed: **May 5, 2022**

(80) **Hague Agreement Data**

Int. Filing Date: **May 5, 2022**

Int. Reg. No.: **DM/223165**

Int. Reg. Date: **May 5, 2022**

Int. Reg. Pub. Date: **Sep. 16, 2022**

(30) **Foreign Application Priority Data**

Dec. 28, 2021 (CN) 202130867563.1

(57) **CLAIM**

The ornamental design for a laptop computer, as shown and described.

DESCRIPTION

1. Laptop computer
2. Laptop computer
- 1.1 : Front
- 1.2 : Back
- 1.3 : Left
- 1.4 : Right
- 1.5 : Top
- 1.6 : Bottom
- 1.7 : Front, right side perspective view
- 1.8 : Front, left side perspective view
- 2.1 : Front
- 2.2 : Back
- 2.3 : Left
- 2.4 : Right
- 2.5 : Top
- 2.6 : Bottom
- 2.7 : Front, right side perspective view
- 2.8 : Front, left side perspective view

The broken lines shown in the drawings illustrate portions of the laptop computer and form no part of the claimed design.

1 Claim, 16 Drawing Sheets
